UNITED STATES PATENT OFFICE.

THOMAS C. SHEEHAN, OF JERSEY CITY, NEW JERSEY, ASSIGNOR TO DURHAM DUPLEX
RAZOR COMPANY, OF NEW YORK, N. Y., A CORPORATION OF NEW YORK.

HONING-MACHINE.

1,090,577.

Specification of Letters Patent. Patented Mar. 17, 1914.

Application filed June 30, 1910. Serial No. 569,718.

To all whom it may concern:

Be it known that I, THOMAS C. SHEEHAN, a citizen of the United States, residing at Jersey City, county of Hudson, and State of New Jersey, have invented a new and useful Improvement in Honing-Machines, of which the following is a specification.

This invention relates to a machine for honing razor blades, particularly blades of the thin replaceable type used in connection with certain razors of the safety type, and its main object is to provide a machine for this purpose in which successive blades are automatically honed so that the cutting edges of all will be exactly alike.

A further object is to provide a machine in which blades are forwarded in a right line to and past the honing device so that there will be no bending of the blades and consequent deformation of the delicate cutting edges after the honing operation is completed.

Still another object is to provide a machine in which the blade forwarding devices move continuously at a uniform speed so that all blades will be subjected to a uniform honing action.

Still another object is to provide a machine simple in construction, efficient, readily adjustable for wear, and not liable to get out of order.

With these and other objects not specifically mentioned in view, the invention consists in certain constructions and combinations which will be hereinafter fully described, and then specifically set forth in the claims hereunto appended.

In the accompanying drawings, which form a part of this specification and in which like characters of reference indicate the same or similar parts, Figure 1 is a plan view of a device constructed in accordance with the invention, Fig. 2 is a side elevation of the structure shown in Fig. 1, with certain parts broken away to show other parts, and Fig. 3 is an enlarged detail view, partly sectional, of one of the honing devices.

In carrying the invention into effect, there is provided means for forwarding a blade with one of its edges exposed, and this means may vary within wide limits. While, in certain constructions, individual clamps moving intermittently or continuously may be used for this purpose, or holding means

common to a plurality of blades moving intermittently; in the best constructions and as shown, continuously moving forwarding means is employed including a pair of belts 1 and 2 which coöperate to forward a blade or blades placed between them, into the range of action of honing devices. When belts are employed for this purpose, they may be variously mounted. In the device selected to illustrate the invention, however, the belts are mounted to continuously move in horizontal planes and to support and forward blades with their upper edges exposed to and in a right line past the honing devices, so that there can be no deformation of the delicate edges of the blades after the honing operation is completed. To this end, the belt 1 is arranged to run over pulleys 3 and 4, and the belt 2 is arranged to run over pulleys 5 and 6. The pulley 3 is fixed upon the upper end of a short shaft 7 journaled in a bearing 8 formed on a table 9 which is supported by a frame 10. This frame 10 is the main frame of the machine. Upon the lower end of the shaft 7 is fixed a worm wheel 11 in mesh with a worm 12 fast on a horizontal shaft 13 which is the main power shaft of the machine. This shaft carries the usual pulley 13' by means of which it is turned in a well known manner. Similarly, the pulley 5 is fixed upon the upper end of a shaft 14 journaled in a bearing 15 formed on the table 9 before referred to. Upon the lower end of this shaft, is fixed a worm wheel 16 in mesh with a worm 17 fast on the shaft 13. The pulleys 4 and 6 are respectively loosely mounted on studs 18 and 19 secured in the table 9.

When blades having a perforation, or perforations, therein, are to be honed, means engaging the perforation, or perforations, is provided for positively forwarding the blade or blades. This means may vary within wide limits. As shown, the belt 1 is provided with a series of pins 20 engaging the perforation of a blade 21, one edge of which projects above the belts 1 and 2 in an exposed position. There is provided a stationary guide 22 mounted on the table 9 and extending along the front side of the machine and around the side of the pulley 4. This guide is spaced from the belt a distance substantially equal to the thickness of the blades to be honed, so that it coöperates with the belt to hold a blade on the pins 20 dur-

ing the first part of the forwarding operation, blades being placed between the belt and guide at 23. It will be readily understood that when a blade reaches the far end 5 of the stationary guide, it is caught between the two belts and forwarded still farther in a right line by the coöperating action of the belts.

A rotating hone located in the path of the 10 exposed edge of a blade is provided, and this hone may vary within wide limits. In certain constructions, a single hone may be employed. In the best constructions, however, and as shown, a series of rotating hones 15 is employed, and these hones are alternately oppositely positioned on either side of and in the path of the exposed edge of the blade, so that both sides of the exposed edge of a blade may be honed during the forwarding 20 operation. Each of the hones shown in the drawings consists in a stone wheel 24 fixed upon one end of a short shaft 25 journaled in a tilting bearing 26. This bearing is pivoted at 27 to a bracket 28. The bracket 25 28 is provided with a series of elongated slots 29 through which a series of clamping screws pass for the purpose of clamping the bracket on the table 9 before referred to. An adjusting screw 31 of well known construction 30 is provided for the purpose of adjusting the bracket 28 toward or away from the belts 1 and 2. A pair of adjusting screws 32, 33 are provided, which are threadled into the tilting bearing 26 and the heads 35 of which bear against the bracket 28. It will be readily understood that by the use of the mechanism just described, the hone may be adjusted toward or away from the belts and exposed edge of a blade carried thereby, and that it may also be adjusted by a tilting action to vary the angle of the face of the hone with the faces of a blade in the 40 belts. Upon the other end of the shaft 25 is fixed a pulley 34 driven by a belt 35 running 45 thereover and also over a pulley not shown on a line shaft over the machine.

It will be noted that the axis of the rotating hone, indicated by the broken line ϵ , lies in a plane intersecting the exposed edge 50 of the blade, Fig. 3; and also in a plane crossing the forwarding means at an obtuse angle, Fig. 1. It is to be understood, however, that this arrangement is not absolutely necessary, and in certain constructions, other 55 arrangements of the hones with respect to the belts or other forwarding devices may be employed.

For the purpose of holding a blade against the rotating hone during the honing operation, there is provided a guide opposite and coöperating with the hone, and this guide may vary within wide limits. As shown, however, this guide includes a bracket 36 secured to the table 9 opposite the operating

edge of the hone 24. Upon this bracket is 60 mounted a frame 37 having two depending lugs 38 and 39, the former within the bracket 36, and the latter outside the same. The lug 39 carries a stud 40 which passes through a suitable aperture in the wall of 70 the bracket 36 and into the lug 38. This stud is loosely fitted in the apertures of the bracket and lug 38 so that it may slide freely therethrough. Coiled around that part of the stud lying between the lug 38 and the 75 rear wall of the bracket 36, is a spring 41 the function of which is to press the frame 37 against the exposed edge of a blade held between the belts 1 and 2, and thereby hold it against the hone 24. Movement of this 80 frame toward the hone is limited by means of an adjusting screw 42 of well known construction.

All the hones are alike, and it is deemed unnecessary to repeat a detailed description 85 of each of them. Such description is, therefore, omitted in the interest of brevity and clearness.

In the operation of the device shown, 90 blades are successively placed by hand between the belt 1 and guide 22 at 23, with the pins 20 engaging the perforations in the blades. By the coöperative action of the belt and guide, the blades are forwarded to the far end of the guide where they are 95 caught between the belts 1 and 2 and forwarded past the hones to the point where the belt 1 turns around the pulley 3. Here they are forced from the pins 20 by the bending of the belt, and drop into a suitable receptacle placed upon the table at this point. 100

Changes and variations may be made in the structure by means of which the invention is carried into effect. The invention, therefore, is not to be restricted to the precise details of the structure shown and described.

What is claimed is:

1. In a honing machine, the combination 110 with means including a pair of belts contacting with and coöperating to forward a blade with one of its edges exposed, and a rotating hone in the path of the exposed edge of the blade.

2. In a honing machine, the combination 115 with means comprising a pair of belts contacting with and coöperating to forward a blade with one of its edges exposed, and a rotating hone in the path of the exposed edge of the blade and with its axis lying 120 in a plane intersecting the edge of the blade.

3. In a honing machine, the combination 125 with means comprising a pair of belts contacting with and coöperating to forward a blade in a right line with one of its edges exposed, and a rotating hone in the path of the exposed edge of the blade, and with its

axis lying in a plane intersecting the edge of the blade.

4. In a honing machine, the combination with means for forwarding a blade with one of its edges exposed, and a rotating hone in the path of the exposed edge of the blade and with its axis lying in a plane intersecting the edge of the blade and also in a plane crossing the forwarding means at an obtuse angle.

5. In a honing machine, the combination with means for forwarding a blade with one of its edges exposed, of a series of rotating hones alternately positioned on either side of and in the path of the exposed edge of the blade and with their axes lying in planes intersecting the edge of the blade and also in planes crossing the forwarding means at obtuse angles.

20 6. In a honing machine, the combination with means for forwarding a blade with one of its edges exposed, of a series of rotating hones alternately positioned on either side of and in the path of the exposed edge of the blade and with their axes lying in planes intersecting the edge of the blade and also in planes crossing the forwarding means at obtuse angles, and a series of independently adjustable supports one for each hone.

30 7. In a honing machine, the combination with means for forwarding a blade with one of its edges exposed, of a rotating hone in the path of the exposed edge of the blade, and a yielding guide opposite and co-operating with the hone to hold the exposed edge of the blade against the hone.

8. In a honing machine, the combination with means for forwarding a blade with one of its edges exposed, of a rotating hone in the path of the exposed edge of the blade, and a spring pressed guide opposite and co-operating with the hone to hold the exposed edge of the blade against the hone.

45 9. In a honing machine, the combination with means for forwarding a blade with one of its edges exposed, of a rotating hone in the path of the exposed edge of the blade, and an adjustable spring pressed guide opposite and co-operating with the hone to hold the exposed edge of the blade against the hone.

50 10. In a honing machine, the combination with means comprising a pair of belts contacting with a blade and continuously moving in horizontal planes for forwarding the blade with one of its edges exposed, of

a hone rotating in inclined planes and in the path of the exposed edge of the blade.

11. In a honing machine, the combination with means including a pair of belts 60 continuously moving in horizontal planes for forwarding a blade between the belts with its upper edge exposed, of a hone rotating in inclined planes and in the path of the upper edge of the blade.

65 12. In a honing machine, the combination with means including a pair of belts and a stationary guide for forwarding a blade with one of its edges exposed, of a rotating hone in the path of the exposed edge of the blade.

70 13. In a honing machine, the combination with continuously moving means adapted to engage a perforation in a razor blade to forward it with one of its edges exposed, and a rotating hone in the path of the exposed edge of the blade and with its axis lying in a plane intersecting the edge of the blade.

75 14. In a honing machine, the combination with means including a pair of coöperating 80 belts one of which is provided with pins adapted to engage a perforation in a razor blade to forward it with one of its edges exposed, and a rotating hone in the path of the exposed edge of the blade.

85 15. In a honing machine, the combination with a pair of coöperating belts for forwarding a blade with one of its edges exposed, of a rotating hone in the path of the exposed edge of the blade, and a guide opposite and coöperating with the hone to hold the exposed edge of the blade against the hone.

90 16. In a honing machine, the combination with a pair of belts coöperating to forward 95 a razor blade with one of its edges exposed, of a rotating hone in the path of the exposed edge of the blade, and an adjustable tilting support for the hone.

100 17. In a honing machine, the combination with a pair of belts coöperating to forward a razor blade with one of its edges exposed, of a rotating hone in the path of the exposed edge of the blade, and an adjustable support for the hone.

105 In testimony whereof, I have signed my name to this specification in the presence of two subscribing witnesses.

THOMAS C. SHEEHAN.
